UNITED STATES PATENT OFFICE

ARNOLD A. ANGELL, OF CHICAGO, ILLINOIS, ASSIGNEE TO THE TURNER TANNING MACHINERY COMPANY, OF PORTLAND, MAINE, A CORPORATION OF MAINE

SEASONING MACHINE

Application filed September 16, 1927. Serial No. 219,977.

The invention relates to machines for applying liquid dressings or seasonings to hides, skins, leather and other similar pieces of work.

Machines of this type commonly employ brushes for applying and distributing the liquid dressing and in time the brushes become worn and must be adjusted with respect to the surface of a work support to compensate for the loss in the length of the bristles of the brushes. Furthermore, in replacement operations, brushes of different diameters must be adjusted properly with respect to the work support. Where the work support is a drum it is important that the lines of contact of the brushes with the cylindrical surface of the drum shall remain the same for all diameters of brushes. Accordingly, the present invention provides improved means adapted for adjusting the brushes of a machine of the type referred to so as to maintain the same lines of contact with the drum whether the brushes be large or small or whether brushes initially of a standard size become smaller due to wearing away of their cylindrical surfaces. In the illustrated machine, each brush is adjustable in a plane passing through the axis of the drum, so that its line of contact with the drum is always the intersection of this plane with the cylindrical surface of the drum. Preferably the supports for each brush are arranged to be adjusted in a plane parallel to the plane just mentioned, and each support is provided with a brush-supporting bearing which is offset into the plane passing through the drum axis. The advantages of this construction are particularly evident in connection with thickly bristled brushes which may be so positioned as to operate on the work with the extreme end portions of the bristles, thus minimizing spattering of the liquid dressing and at the same time producing a more uniform distribution of the dressing on the work characterized by

the absence of brush marks upon the finished surface. With brushes thus positioned with respect to the work it is important that when the proper relationship between a given brush and the curved surface of the work support has once been established it should not be changed by relative lateral displacement of brush and work support during adjustment of the brush nor in the operation of replacing a worn out brush by a new brush of considerably greater diameter. Another advantage of the construction of brush supporting and adjusting means herein disclosed resides in the fact that proper spacing of the brushes with respect to each other is maintained at all times, thereby insuring, in the co-operation of the brushes with the drum, a more certain and perfect feeding of the work than could otherwise be obtained. This will be more readily appreciated when it is recalled that in prior constructions the shank portions of hides and skins not infrequently become a source of difficulty by escaping from the control of the brushes in such manner that these portions, and often other portions adjacent thereto, become folded over upon themselves and receive the dressing liquid upon both grain and flesh surfaces, such improper and undesirable results being due, in part at least, to improper spacing of the brushes. Hence, during adjustment of the brush supports or of the bearings carried thereby, the axis of the brush remains in the described plane which is radial to the drum and the line of contact of the brush with the drum will always be the same irrespective of the diameter of the brush.

Other features of the invention relate to a novel feeding-in table comprising a section having spaced vertical ribs designed to support the work and guide it to the drum while at the same time presenting the minimum of surface for receiving any accidental spattering of the dressing liquid from the liquid applying brush located above the feed-

ing-in table. Preferably, and as illustrated, the table has flanges for strengthening the spaced ribs operative also to collect any spattered liquid material and direct it to a receptacle provided for the purpose.

These and other features of the invention will now be described in detail and pointed out in the appended claims.

In the drawings,

10 Fig. 1 is a plan view from above of a machine illustrating one embodiment of the invention;

15 Fig. 2 is a side view of the machine shown in Fig. 1, looking from the right in said figure, the supply tank for the liquid dressing being omitted;

20 Fig. 3 is a vertical, horizontal section of the machine shown in Fig. 1;

25 Fig. 4 is a detail view showing the mounting mechanism for the brushes;

30 Fig. 5 is a detail view taken along the line V—V of Fig. 2 looking in the direction of the arrows;

35 Fig. 6 is a detail view of a locking mechanism for a gear shift mechanism shown at the upper left portion of Fig. 2;

40 Fig. 7 is a detail view of a number of the parts shown in Fig. 6;

45 Fig. 8 is a view of the wiper mechanism shown in section at the left of Fig. 3;

50 Fig. 9 is a section of a wiper mechanism taken along the line IX—IX of Fig. 8;

55 Fig. 10 is a section along the line X—X of Fig. 8;

60 Fig. 11 is a section along the line XI—XI of Fig. 8;

65 Fig. 12 is a cross sectional view along the line XII—XII of Fig. 4;

70 Fig. 13 is a perspective view of the cone-shaped locking member shown in section in Fig. 12;

75 Fig. 14 is a general view of the circulatory system for the liquid dressing;

80 Fig. 15 is a plan view from above of the pan for supplying the liquid to the brushes;

85 Fig. 16 is an end view of the pan looking from the right in Fig. 15 and

90 Fig. 17 is a sectional view of the pan taken along the line XVII—XVII of Fig. 15.

95 In the illustrated machine, which is designed for applying liquid dressing such as seasoning fluid to hides, skins, leather and the like, there is provided a slanting table 20 over which a piece of work may be fed to a drum 22 mounted for rotation with a shaft 24 turning in the direction of the arrow in Fig. 3. For co-operation with the drum 22 there is provided a plurality of brushes 26, 28, 30, 32, each turning in the direction of the arrow in Fig. 3, and each operating to spread a seasoning liquid over the surface of a piece of work while the latter is supported by the drum 22. In addition to spreading the liquid upon the work, the brush 26 serves also as a liquid supplying brush since it is arranged

100 to receive liquid from a distributing roll 34 which is arranged to dip into liquid within a liquid containing pan 36. At the right of the drum 22 there is shown a discharging table 38, the upper portion of which is shown as a sharp edged blade 40 for taking the piece of work from the drum and directing it downwardly along the slanting surface of the table 38 so that it may finally be deposited upon an endless traveling belt 42 which, moving in the direction of the arrow in Fig. 3, carries the work along in a horizontal position where it may be swabbed while it lies in a flat position on, and moves with, the moving belt 42. Usually a man stands at each side of the moving belt and swabs the piece of work, thereby smoothing and finishing the coated surface and touching up any uneven spots. For a more complete disclosure of the endless traveling belt and the purposes for which it is provided, reference should be had to United States Letters Patent No. 1,463,542, granted July 31, 1923, upon application of Arnold A. Angell.

105 Means is provided for adjusting each brush in directions toward and from the drum, the construction being such that this adjustment may be accomplished while maintaining the axis of a given brush in a plane radial to the drum 22 so that the lines of contact of the brushes with the surface of the drum will remain the same for all diameters of brushes and as the bristles of the brushes become shortened through wear. In the construction shown, the adjusting means for one brush is the same as that for every other brush so that a description of one adjusting mechanism will serve for all. Referring particularly to Fig. 4 of the drawings, it will be observed that a hollow post 50 is provided with an interiorly screw threaded socket 52, the post 50 being commonly cast integral with the frame 54. In one instance the post 50 is part of a clamp member 56 which forms part of the bearing for the shaft 24. As stated, the post 50 contains an interiorly screw threaded socket 52 adapted to receive the screw threaded end of a hollow rod 60, the upper end of which is provided with a hand wheel 62 rigidly secured thereto. Extending through the hollow rod 60 is a smaller rod 64, the upper end of which is screw threaded and provided with a winged nut 66. At its lower end the rod 64 is provided with a tapered plug 68 shown in Fig. 4 and also in Figs. 12 and 13, the plug 68 being screw threaded upon the end of the rod 64. The plug 68 is receivable within a socket in the lower end of the rod 60 which is bored out to provide a socket having tapered surfaces and is also slit at six places as indicated at 70 in Fig. 12, the arrangement being such that, upon pulling the tapered plug 68 inwardly within the socket in the rod 60, split portions 72 of the rod 60 will be spread apart

to engage firmly with the surfaces of the socket 52, thereby fixedly securing the bar 60 in adjusted relation to the post 50. To adjust the bar 60 relatively to the post 50 the wing nut 66 will first be manipulated to free the rod 64 for movement axially toward the post 50. A sharp blow upon the outer end of the rod 64 or upon the nut 66 will drive the rod 64 in the desired direction to loosen the plug 68. When this has been accomplished, the hollow rod 60 may be turned in the proper direction, by means of the hand wheel 62, to adjust the associated end of the brush with respect to the drum 22. After the adjustment has been accomplished the wing nut 66 will be tightened to draw the plug 68 into clamping relation within the split portions 72 to hold the rod 60 in its adjusted position. It will be observed that the rod 60 is provided with a sleeve 74 having a projecting portion 76 which provides a bearing surface for shaft 78 of the brush, the other part of the bearing for the shaft 78 being provided by a clamping member 80 adapted to be secured in clamping relation to the first bearing member by means of a threaded bolt 82, the arrangement being such that the shaft 78 of any one of the brushes may be readily removed from the machine and as readily replaced by another brush-carrying shaft. Upon inspection of Fig. 4 it will be observed that the axial line of any given rod 60 is parallel with a line joining the center of the shaft 24 with the center of the shaft 78 associated with the given rod 60, the distance between the two lines just mentioned being such that adjustment of the rod 60 moves the shaft 78 in a plane radial to the drum 22. Since two rods 60 serve as supports for each brush, it is clear that adjustment of one or both of the rods 60 will move the supported brush with its axis always in a plane radial to the drum. In order that the brush may be held firmly in operative position, the sleeve 74 is arranged to be maintained fixedly against a shoulder 84 by means of a nut 86 screw threaded upon the exterior surface of the rod 60.

For supplying seasoning fluid to the brush 28 there is provided, as has already been stated, the distributing roll 34 mounted so as to dip into the fluid in the pan 36. Conveniently the distributing roll 34 is mounted in a bearing provided by a sleeve 90 carried by a rod 92 adjustable in a post 94, the construction and arrangement of sleeve 90, rod 92 and post 94, relatively to each other, being similar in all respects to the construction and arrangement of rod 60, sleeve 74 and post 50, relatively to each other. The reason for the adjusting means for the distributing roll 34 is that the roll must be adjusted toward the brush 26 as the latter becomes worn and is adjusted toward the drum 22. In order that the distributing roll 34 may serve to lift the seasoning fluid into contact with the brush 26 it is fluted, as shown most clearly in Fig. 1 of the drawings. Since the amount of liquid fed to the brush 26 by the distributing roll 34 depends upon the speed of the latter, means is provided for varying the speed in accordance with the judgment of the operator, as will be hereinafter described.

For supplying the pan 36 with a liquid dressing such as seasoning liquid there is provided a liquid circulating system comprising a pipe 100 which is supported in the pan 36 by having screw threaded ends 102 receivable in interiorly screw threaded sockets 104 at each end of the pan 36, a screw threaded plug 106 being provided for closing the outer end of each socket 104. At a point between the ends of the pipe 100 the latter is provided with an elbow joint 108 screw threaded upon the adjacent ends of the two sections of the pipe 100, the elbow joint 108 being adapted to receive, and have fixedly secured thereto, one end of a flexible tube 110, the other end of which is fixedly secured to a supply pipe 112, the flexible tube or hose 110 being provided to offer no obstruction to the removal of the pan 36. Upon inspection of Figs. 14 and 17, it will be observed that the pipe 100 is provided with numerous perforations 114 arranged in two rows upon opposite sides of the pipe and directed downwardly in a slanting direction so as to direct the incoming liquid toward the bottom of the pan 36, the arrangement being such, as will be hereinafter described, that the liquid enters the pan 36 through the holes or perforations 114 at such a velocity as to cause constant agitation of the liquid in the pan throughout the length thereof to prevent settling of the pigments in the liquid. The liquid in the pan 36 is kept at a constant level considerably above the openings or perforations 114 in the pipe 100 since, if the liquid were permitted to descend below or to the level of the openings or perforations, there would result a foaming of the liquid which would be objectionable since it would cause a spotty condition of the work. As a part of means for maintaining the level of the liquid at a predetermined height in the pan 36 and above the perforations 114, there is provided at one end of the pan a weir 116 over which the excess liquid may flow into a discharge pipe 118 which carries the liquid back to a supply tank 120. In order that the pan 36 may be emptied upon occasion there is provided an opening 122 in the weir 116 at the level of the bottom of the pan, it being understood that so much liquid enters through the perforations 114 that the level of liquid in the pan is maintained at the upper edge of the weir 116 above the level of the perforations 114 with a constant discharge over the weir in order to afford additional insurance against any settling of the pigments in the liquid by 130

maintaining a constant circulation of the seasoning liquid. Where the discharge pipe 118 enters the supply tank 120 there is provided a screen 124 for retaining particles of 5 pigment of undesirable size. In the bottom of the tank 120 is a stirrer 126 supported and rotated by a shaft 128 in turn supported in a journal at the upper end of the tank and provided with a bevel pinion 130 arranged 10 in mesh with a bevel gear 132 fixedly secured to a shaft 134 arranged to be flexibly coupled at 136 to the drum shaft 24, the arrangement being such that while the machine is running the stirrer 126 is constantly in operation. 15 Leading from the bottom of the tank 120 is a pipe 140 which leads to a rotary pump 142 driven by a chain 144 (Fig. 3) from the main shaft of the machine. The pump 142 discharges the fluid into a vertically arranged 20 pipe 146, a valve controlled outlet being provided at 148 for emptying the whole system of the contained seasoning liquid or of cleansing water when the latter is run through to clean out the circulatory apparatus. Upon 25 inspection of Fig. 14 it will be observed that the vertical pipe 146 is connected by an elbow to the pipe 112 heretofore referred to as the supply pipe for the pan 36. Vertical pipe 146 is provided with an outlet connection at 30 148 controlled by a valve 150 so that upon proper manipulation of the valve 150 all of the seasoning liquid may be pumped out of the system and emptied into a suitable receptacle placed below the outlet connection 148. 35 This removal of the seasoning liquid is a step preliminary to the cleaning out of the circulatory system by means of wash water introduced into the tank 120 pumped through the system by the pump 142 and finally discharged through the outlet or drain pipe at 40 148. The vertical pipe 146 is also provided with a valve 152 for the purpose of controlling the amount of flow of the seasoning liquid and the pressure within the pipe 100. 45 It will be understood that the pump 142 with its connections to the supply pipe 112 constitutes the other part of the means for maintaining the level of the liquid at a predetermined height in the pan 36, the weir 116 being the part first mentioned and described. 50 Means is provided in the illustrated machine for wiping the drum 22 to remove any of the seasoning liquid which may have been brushed upon exposed portions of the drum 55 while the brushes are operating upon a piece of work which may have left uncovered portions of the drum due to the irregular shape of the work. Upon reference to Fig. 3 of the drawings it will be observed 60 that the wiper mechanism 160 is located in the lower left quadrant of the drum below the feeding-in table 20. The wiper mechanism comprises a supporting bar 162 (Fig. 8) carried by brackets 164 which are shown 65 as integral with side frames 166 of the ma-

chine. As most clearly shown in Figs. 9, 10 and 11 of the drawings, the brackets 164 are inclined to the vertical and each bracket is provided with a lip 168 at its upper end and a lug 170 at its lower end. Threaded through the lug 170 is a screw 172 provided with a hand wheel 174. As shown most clearly in Figs. 8 and 10, the ends of the bar 162 are shaped to engage under the lips 168 of the brackets 164 so that upon manipulation of the screw 172 the bar 162 may be forced into firm engagement with the lips whereby the bar is held fixedly in operative position. To release the bar 162 it is necessary merely to reverse the movement of the screws 172 a sufficient distance to permit the escape of the edges of the bar from the lips 168 when the bar may be turned about its points of contact with the screws to expose a wiper 176 for inspection and for cleaning or for replacement. The wiper 176 is a strip of rubber, although felt or other suitable material may be used. It is fitted into a deep groove or slot which extends throughout the greater part of the length of the supporting bar 162, as will be clear upon an inspection of Fig. 8 of the drawings. In the bottom of this same groove or slot is a bar 178 of metal, though other suitable material may be employed in making the bar. Extending through screw threaded openings in the lower edge of the bar 162 are screw threaded adjusting members 180, each provided with a hand wheel 182. Upon adjusting the screw threaded members 180 in the proper direction 100 the bar 178 is forced toward the mouth of the slot or groove, thus forcing the wiper 176 to project further from the groove in the bar 162, provision being made in this way for causing the wiper to engage the drum 20 and for adjusting the wiper to secure efficient operation thereof in spite of the wear which takes place upon the edge which engages with the drum. 105 Accumulation of lint and dust from the leather, as well as bristles and waste seasoning liquid from the surface of the drum, collecting behind the wiper, render it necessary to clean the wiper at intervals. To do this the screws 172 are loosened by proper manipulation of the hand wheels 174, thus permitting the bar 162 to slide down the incline of the brackets 164 until the upper edges of the bar 162 are freed from the lips 168. Then the bar 162, with all the parts carried thereby, may be swung about the pivotal points provided by the ends of the screws 172 to such a position that the wipers 176 and parts adjacent thereto are exposed for cleansing. Subsequently, the bar 162 may be swung back into its resting position against the brackets 164 and returned to locked position by proper manipulation of the screws 172 without any loss of adjustment of the wiper 176 with respect to the drum 22. Con- 110 115 120 125 130

veniently, the bar 162 may be utilized as a trough to catch drippings from the feeding-in table 20. For this purpose the bar 162 has a flange 190 which is inclined from each end of the bar toward a median point so as to guide the collected liquid to a discharge pipe 192 (Figs. 3, 8 and 9). Below the lower end of the discharge pipe 192 is a collecting pan 194 positioned to receive drippings from both the feeding-in table 20 and the discharge table 38. Conveniently and as shown, the collecting pan 194 has at its low point a discharge pipe 196 below which a receptacle may be placed to receive the waste liquid.

15 While the feeding-in table 20 may be of any usual or well-known construction, it is preferably of a special construction, as shown, designed to prevent as much as possible soiling of the under surface of the work as the latter is being inserted into the machine. Since the brush 26 which receives the treating liquor from the distributing roll 34 is located directly above the inner end of the table 20 there is the possibility of a certain amount of spattering of the liquid upon the upper end of the table. The chances of soiling the incoming work from such spattering are minimized by the provision of a plurality of narrow ribs 200 (Figs. 1 and 3) which will hold but little of the liquid and collect none of it, these ribs supporting those parts of the work which might be soiled as a result of spattering of the liquid. Between the ribs 200 are supporting flanges 202 which also serve to collect any liquid spattered from the brush 26 and direct it downwardly through openings 204 through which the liquid may drop to the trough provided by the wiper bar 162 and its associated flange 190 (Fig. 8) as before described. The rest of the table 20 may have a plain, work supporting surface 206, as shown most clearly in Figs. 1 and 3.

20 Means is preferably provided for varying the speed of the distributing roll 34 in order that a greater or a less amount of seasoning liquid may be fed to the brush 26 for application to a piece of work in accordance with the judgment of the operator. As shown, the distributing roll 34 is provided with a driving shaft 210 having a key-way 212 (Figs. 1 and 2) throughout its end extension 213. Carried by the extended end 213 of the shaft 210 and free to slide laterally on it is a sleeve 214 having a key which fits in the key-way so that the sleeve must rotate with the shaft 210. As a part of the sleeve 214 is a gear 216, it being understood that the gear may be separable from and rigidly attached to the sleeve 214. Freely rotating on the sleeve 214 is a lever 218 having a handle 220, the lever 218 carrying at its end opposite the handle 220 a gear 222 shown in Fig. 2 as in mesh with the gear 216 and also with a gear 224

which is the largest gear of a whole series of gears 226 secured to the shaft 24. It will be readily understood then that the shaft 210 of the distributing roll 34 is driven from the drum shaft 24 through the chain of gears 224, 222, 216. If it be desired to change the speed of the shaft 210 the operator may simply depress the handle 220, thereby lifting the gear 222 out of contact with the gear 216 and follow this with a shifting of the sleeve 214 along the extended end 213 of the shaft 210 until one of the smaller of the series of gears 226 is located below the gear 222 which may then be lowered into contact with the selected gear.

If desired, the sleeve 214 may carry fixedly secured thereto a smaller gear 227 (Fig. 2) with which the gear 222 may be made to mesh by shifting it from the position shown in Fig. 2 to a bearing 230 in the same supporting lever 218. When the gear 222 is in mesh with gear 216, it may be made to mesh with any one of the nine gears of the series of gears 226, thus providing nine changes of speed. When the gear 222 has been changed so that it is supported by the bearing 230, in which case it is in mesh with the smaller gear 227 on the sleeve 214, it is clear that nine other and distinct changes may be secured when the gear 222 in its new position is caused to mesh with the different gears in the series of gears 226.

By the simple arrangement of gear shift shown in Figs. 1 and 2 there are provided eighteen changes of speed for the distributing roll 34. For holding the gear 222 in mesh with the selected gear of the series of gears 226 there is provided a locking means comprising a link 232 (Fig. 2) pivoted at 234 to the lever 218 and having a guideway 236 (Fig. 6) for a slide block or clamp 238 and a bar 240. The bar 240 is rigid with the frame of the machine and provides a rigid support to which the link 232 may be locked to hold the gear 222 in mesh with the selected gear of the series of gears 226. For locking the link 232 to the bar 240 there is provided, as already stated, the slide block or clamp 238, (Figs. 6 and 7) which has a projecting screw threaded portion 242 provided with a nut 244 to which is pivotally secured a handle 246. Upon manipulating the handle 246 in the direction to tighten the nut 244 on portion 242, the slide block or clamp 238 is fixedly clamped to the link 232 and at the same time to the bar 240 through interaction between clamp 238 link 232 and bar 240. Upon turning the nut 244 in the opposite direction, the slide block 238 is released and moved to releasing position by means of a spring 248 upon a stem 250 integral with the slide block or clamp 238. When it is desired to shift the lever 218 and the gear 222 carried thereby, the slide block or clamp 238 is first released through proper manipulation of the handle 246 and the nut 244 operated thereby. Then

110
115
120
125
130

the lever 218 is shifted along with the sleeve 214 upon the key-slotted end 213 of the shaft 210. During this time the link 232 and the parts carried thereby slide axially of the bar 240. When the desired gear in the series of gears 226 is reached, the gear 222 is lowered into mesh therewith and during the accompanying movement of the lever 218 the link 232 slides vertically on the bar 240 in a downward direction to permit of the engagement of the gear 222 with the selected gear on the shaft 24. Then tightening of the nut 244 will serve to hold the gear 222 in its new adjusted position. For preventing injury to the gears when gear 222 is lowered into mesh with a selected gear in the series 226 there is provided, in conjunction with each gear, a flat ring, as indicated at 260 (Fig. 1) the outside diameter of which is equal to the pitch diameter of the associated gear. The result is that each time that the gear 222 is lowered into contact with one of the series of gears 226, a ring 262 associated with gear 222 will contact with the surface of the ring associated with the selected gear to bring about a rolling contact which will prevent injury to the gears and yet keep them at proper mesh.

As before stated, the drum 22 is mounted fixedly upon the shaft 24 to rotate therewith, said shaft being provided with a gear wheel 270 (Fig. 3) arranged to mesh with an intermediate pinion 272, which has a running fit on fixed shaft 282. Pinion 272 is fastened to gear 273 and to sprocket wheel 275 both rotatable on the same shaft 282, gear 273 being driven by pinion 277 fixedly mounted upon a main driving shaft 276, the latter being provided with a pulley 278 adapted to receive a belt arranged to be driven from any suitable source of power (not shown). Fixedly carried by the shaft 276 is a gear 279 (Fig. 2) arranged to be in mesh with a gear 280, which rotates on fixed shaft 282 and is fastened to sprocket wheel 284, around which passes a chain 286, which, at its other end, engages with a sprocket wheel 288 mounted upon a non-rotatable and slidably mounted stub shaft 290 (Figs. 2 and 5). Sprocket wheel 288 is fastened to a sprocket wheel 292 adapted to be engaged by a chain 294 which passes around and in engagement with sprocket wheels 296 secured upon the ends of the brushes 26, 28, 30, brushes 28 and 30 being driven at different speeds, due to a difference in the sizes of the sprocket wheels 296, carried by their respective shafts. Brush 32 is driven separately through a chain 298 arranged to be driven from the sprocket 275 fastened to the pinion 272 which turns on the fixed shaft 282. For driving the horizontally arranged table belt 42, one of its supporting rolls 300 is secured to a shaft 302 journaled in the frame of the machine and provided with a large gear 304 arranged

in mesh with the pinion 272, which in turn meshes with the gear 270 secured to the drum 24, thereby insuring the proper timing of the table belt 42 with respect to the drum 22.

In operating the machine shown in the drawings, the workman places the forward edge portion of a hide or skin or other piece of leather upon the slanting feeding-in table 20 and shoves it upwardly until its forward edge is engaged between the rotating drum 22 and the first brush 26 which are turning in the directions indicated by the arrows in Fig. 3 to feed the work at the same time that the brush 26 applies the dressing liquid which it receives from the distributing roll 34. During the further feed of the piece of work each brush 28, 30, 32 assists both in the feeding of the work by keeping the latter in contact with the drum 22 and in distributing the liquid dressing uniformly over the exposed surface of the work. Finally the forward edge of the work reaches the sharp edge 40 of the delivery table 38 which operates to strip the piece of work from the drum 22, the table 38 directing the piece of work down into position upon the table belt 42 which carries it off to the right in Fig. 3, in a horizontal position for inspection and for such hand swabbing of the surface as may be desirable.

Having thus described my invention, what I claim as new and desire to secure by Letters Patent of the United States is:

1. In a machine for applying a liquid dressing to pieces of work, a drum for supporting the work, a brush for applying the liquid to a piece of work on the drum, a pair of supporting rods for the brush located in a plane parallel to and at one side of a plane defined by radii of the drum, and bearing members carried by the rods and arranged to support the brush with the axis thereof in the last-mentioned plane, the rods being adjustable to move the brush in directions toward or away from the drum. 106

2. In a machine for applying a liquid dressing to pieces of work, a drum for supporting the work, a brush for applying the liquid to a piece of work on the drum, a pair of posts located in a plane parallel to and at one side of a plane defined by radii of the drum, rods adjustable on said posts in directions toward and away from the drum, and sleeves carried by the rods and having bearings for the brush, the bearings being arranged to locate the axis of the brush in the plane defined by radii of the drum. 115

3. In a machine for applying liquid dressing to pieces of work, a support for pieces of work having an arcuate work supporting surface, a plurality of rotary brushes for applying liquid dressing to a piece of work while the latter is supported on the arcuate surface, means comprising said brushes for feeding the work during application of the liquid 125 130

dressing, and supports for the brushes constructed and arranged for movement to adjust the axes of the brushes toward the arcuate surface in planes radial to said surface.

4. In a machine for applying liquid dressing to pieces of work, a drum, a plurality of rotary brushes for applying liquid dressing to a piece of work while the latter is supported by the drum, said drum and brushes co-operating to feed the work during the application of the liquid dressing, supports for the brushes, and means to cause adjusting movement of the supports to adjust the brushes toward the drum in planes radial to the drum.

5. In a machine for applying liquid to surfaces of pieces of work, provided with a brush for applying the liquid and with means for supporting the work during the operation of the brush, a feeding-in table over which a piece of work may be passed into contact with the brush and the work supporting means, said table having a portion provided with a series of narrow work supporting ribs spaced from each other, and with flanges or web portions joining the ribs along their lower edges to provide a slanting surface spaced from the ribs and from the body portion of the table so that liquid spattered upon the upper portion of the table may be discharged by running down the slanting surfaces provided by the web portions.

6. In a machine for applying liquid to surfaces of pieces of work, provided with a brush for applying the liquid and with means for supporting the work during the operation of the brush, a feeding-in table over which a piece of work may be passed into contact with the brush and the work supporting means, said table having a portion provided with a series of narrow work supporting ribs spaced from each other, and with flanges or web portions joining the ribs along their lower edges to strengthen the ribs.

7. In a machine for applying a liquid dressing to pieces of work, a drum for supporting the work, a brush for applying the liquid to a piece of work on the drum, and a brush supporting and adjusting means connecting the axis of the brush rigidly but adjustably with the axis of the drum, comprising a pair of brush-supporting posts, each post having a socket, rods adjustable in the sockets of said posts in directions toward and away from the drum, sleeves carried by the rods for providing bearings for the brush, the lower end of each rod having an expandable portion, and means for expanding said portion in each rod to cause locking of the rod in adjusted position with respect to the post.

8. In a machine for applying a liquid dressing to pieces of work, a support for the work having a work supporting surface, a brush for applying the liquid to a piece of work on the support, and a brush supporting and adjusting means rigidly but adjustably connecting

the axis of the brush and the axis of the work support comprising a pair of brush-supporting posts, each post having a socket, rods adjustable in the sockets of said posts in directions toward and away from the work support, sleeves carried by the rods for providing bearings for the brush, and means for expanding the lower end of each rod to lock it within the socket of its associated post.

9. In a machine for applying a liquid dressing to pieces of work, a support for the work having a work supporting surface, a brush for applying the liquid to a piece of work on the support, and a brush supporting and adjusting means connecting the axis of the brush rigidly but adjustably with the work support comprising a pair of brush-supporting posts, rods adjustable on said posts in directions toward and away from the work support, sleeves carried by the rods for providing bearings for the brush, and means for expanding the lower end of each rod to lock it in adjusted relation to its associated post.

10. In a machine for applying liquid dressing to pieces of work, means for supporting a piece of work having a work supporting surface, a rotary brush for applying liquid dressing to a piece of work on the work supporting surface, and a brush supporting and adjusting means connecting the axis of the brush rigidly but adjustably with the work supporting means comprising a pair of brush-supporting posts, rods adjustable in said posts in directions toward and away from the work supporting surface, bearings for the brush carried by said posts, and means for securing each rod in adjusted position on its supporting post.

11. In a machine for applying a liquid dressing to pieces of work, a drum for supporting the work, a brush for applying the liquid to a piece of work on the drum, a pair of posts in a plane parallel to and at one side of a plane defined by radii of the drum, each post having a socket, rods adjustable in the sockets of said posts in directions toward and away from the drum, sleeves carried by the rods for providing bearings for the brush, the axis of the brush being thus located in a plane defined by radii of the drum, the lower end of each rod having an expandable end, and a plug for expanding the end of the rod to lock the latter within the socket of the post.

12. In a machine for applying a liquid dressing to pieces of work, a drum for supporting the work, a brush for applying the liquid to a piece of work on the drum, a pair of posts in a plane parallel to and at one side of a plane defined by radii of the drum, each post having a socket, hollow rods adjustable in the sockets of said posts in directions toward and away from the drum, sleeves carried by the rods for providing bearings for

the brush, the axis of the brush being thus located in a plane defined by radii of the drum, the lower end of each hollow rod having an expansible end, a plug for expanding the end of the hollow rod, and a rod connected to the plug and operable for drawing the plug tightly into the expansible end of the hollow rod for locking the latter within the post.

In testimony whereof I have signed my name to this specification.

ARNOLD A. ANGELL.
